UNITED STATES PATENT OFFICE.

FRANK A. BURGESS, OF GENEVA, ILLINOIS.

DESIGN FOR A SAD-IRON STAND.

42,522.

Specification for Design.

Patented May 14, 1912.

Application filed February 5, 1912. Serial No. 675,679. Term of patent 7 years.

To all whom it may concern:

Be it known that I, FRANK A. BURGESS, a citizen of the United States, and a resident of the city of Geneva, in the county of Kane and State of Illinois, have invented a new, original, and ornamental Design for a Sad-Iron Stand, of which the following is a specification, reference being had to the accompanying drawing, forming part thereof.

The figure is a perspective view of a support or stand for sad irons, showing my novel design.

I claim:

The ornamental design for a sad iron stand, as shown.

FRANK A. BURGESS.
